UNITED STATES PATENT OFFICE

CLARENCE M. DAVISON, OF BALTIMORE, MARYLAND, ASSIGNOR, BY MESNE ASSIGNMENTS, TO RAILWAY-HIGHWAY DEVICES CORPORATION, OF CHESTER, PENNSYLVANIA, A CORPORATION OF DELAWARE

RAILWAY CROSSING GUARD

Application filed April 2, 1929. Serial No. 351,904.

This invention relates to improvements in guards or barriers for use at railroad grade crossings.

The barrier is of the horizontally and vertically swinging type adapted to be positioned across a roadway with means for yieldingly resisting the horizontal movement, whereby, upon impact of a vehicle with the barrier, the latter may swing to one side, but the resistance offered such movement will bring the vehicle to a full stop within a distance less than that between the original position of the barrier and the railroad tracks.

An object of the invention is to provide a barrier of this type which will withstand practically any stresses placed upon it, the member against which the vehicle impacts being of a flexible nature and preferably normally flexed, whereby tremendous strains are necessary to rupture it, as distinguished from a taut or rigid barrier which would be either ruptured or permanently distorted under similar strains. Preferably, this vehicle impacting member or barrier proper is in the form of a cable which, in position across the roadway is normally deflected in a horizontal plane in the direction of movement of vehicles approaching the crossing. By having the cable normally deflected, its ends may be fixedly secured to the member provided for supporting and raising it and the retardation of the vehicle is accomplished solely by suitable snubbing mechanism to which the support is adapted to be detachably connected.

A further object is to provide a barrier of this nature which may be produced and installed at a comparatively low cost.

Preferably, the invention also seeks to provide means for preventing sagging of the cable to a point below the vertical center of any vehicle wheel, such means being capable of returning the cable to the proper elevation across the roadway at all times.

With these and other objects in view, the invention consists in certain details of construction and combinations and arrangements of parts, all as will hereinafter be more fully described and the novel features thereof particularly pointed out in the appended claims.

In the accompanying drawings,—

Figure 1 is a plan view of a barrier or guard embodying the present improvements, a vehicle impacting against the barrier and its action thereon being indicated in dotted lines;

Fig. 2 is an elevational view;

Fig. 3 is a detail view showing one of the attaching members for supporting the barrier from its supporting arm;

Fig. 4 is a side elevation of a snubbing device for the guard;

Fig. 5 is a transverse view of the snubber;

Fig. 6 is a detail view of the oil cylinder of the snubber.

In accordance with the present invention, the barrier proper or the member against which an approaching vehicle impacts, is composed of one or more reaches of cable 10 fixedly attached at its ends to a substantially rigid supporting member or arm 11. This is necessary in order that said barrier may be raised and lowered from and to a position transversely of the roadway to be protected, the guard being lowered only when a train is approaching the crossing, as is well known. Said arm 11 is pivoted to swing in a vertical plane about a center 12 and in a horizontal plane about a center 13. Cable 10 may be attached to the pivoted end of arm 11 in any desired manner, but at the opposite end it is preferably passed around an annular member 14 adapted to engage post 19 of a snubbing mechanism that may be of any desired construction. In the present instance, it consists of the post 19 movable along guides 20, and attached to said snubbing post there is a cable 21 passing around a sheave 22, the other end of said cable being attached to a portion of the base on which the entire snubbing mechanism is mounted. Sheave 22 is journaled on the rod or stem 23 of a piston or plunger 24 slidable in an oil cylinder 25 against the pressure of oil in said cylinder, as well as the pressure of a coil spring 26 surrounding the cylinder between a collar 27 thereon and a collar 28 on rod 23. When the snubbing post 19 is moved by a horizontal swinging movement of the barrier, chain or cable 21 tends to move sheave 22 inwardly,

thereby forcing plunger head 24 inwardly. The oil in the cylinder resists such movement of the head but on account of the clearance around the head and the provision of a comparatively small duct 38, the oil between the head and one end of the cylinder gradually escapes to the opposite end, permitting a gradual movement of the sheave 22, the snubbing post 19 and the barrier. After the moving force that has been applied to the barrier is relieved, spring 26 tends to force sheave 22 away from cylinder 25, and under these conditions the oil that has passed head 24 returns rather freely through a comparatively large duct 29 in the head. This duct 29 is provided with a flap valve 30 adapted to close the duct when sheave 22 moves toward the cylinder 25.

In accordance with the present invention, the ability of cable 10 to sustain comparatively heavy loads imposed upon it by vehicles impacting against it at higher speeds, is increased by having it normally flexed, as shown in full lines in Fig. 1. If said cable were positioned at right angles across the road, with both ends fixedly secured to unyielding members it could withstand comparatively little strain. For instance, an 80,000 pound cable, under such conditions, could only carry a load of less than 1,500 pounds, but by having it normally flexed, say five feet, it can carry approximately 30,000 pounds. For this reason, the intermediate portion of arm 11 is offset and the cables 10 normally flexed as shown in Fig. 1.

It is, of course, necessary to prevent the cables 10 sagging to such an extent as to allow them to assume a position below the vertical center of any vehicle wheels. Accordingly, they are supported from the intermediate portion of arm 11 by movable members which will permit the angularity of the flexed cable to change when impacted against by a vehicle, as shown in dotted lines in Fig. 1. Preferably, the cables are supported from said arm by short lengths of cable 40 extending into cylinders 41 on the arm, the inner ends of cables 40 being provided with enlargements 42 to prevent detachment from the cylinders. It is also preferred to interpose comparatively light springs 43 between the enlargements 42 and the ends of the cylinders, so that when the cables 10 are deflected, as indicated in Fig. 1, they will be returned to their normal positions after the vehicle is moved away. It should be mentioned, in this connection, that the retarding and stopping of the vehicle is accomplished solely through the snubbing mechanism, the lightness of springs 43 being such as to have no effect on the retardation of the vehicle. In other words, springs 43 are only strong enough to return the cables to their normal flexed position and prevent said cables sagging. It will also be noted that the horizon-

tal movement of cable 10 is not sufficient to allow the vehicle to impact against the arm 11 so that breakage or distortion of the latter is impossible.

The only conditions under which a vehicle may engage arm 11 is when the vehicle has passed one gate and the gates, which are at opposite sides of the crossing, are lowered before the vehicle clears the crossing. Under these conditions, the gate, then blocking the path of the vehicle, is free to swing horizontally away from the crossing. This is taken care of by having snubbing post 19 formed at one side with a vertically disposed web 31 whose upper surface is inclined to guide the annular member 14 upwardly until it clears the post, as indicated in dotted lines in Fig. 4. After member 14 has cleared the post, the vehicle can push the guard aside and clear the crossing. Upon return of the guard, after the vehicle has thus passed through, member 14 engages a web 32 adjacent post 19 and is elevated thereby so that said member can pass over the post until the opening therein registers with the post, whereupon it will drop into its normal position around said post.

In the drawings, the guides 20 of the snubbing mechanism are shown as extending parallel to the center line of the roadway. Under these conditions, the support 11 must flex somewhat as it swings horizontally, but the extent of this flexing may be reduced by arranging guides 20 at an angle to the center line of the road. For instance, the guide 20 which is between post 19 and the pivotal center of support 11 is essentially a thrust member in that it prevents movement of post 19 laterally toward the road. Therefore, altering the position of the guides 20 so that they are inclined toward the road, flexing of the support will naturally be reduced. Furthermore, the post 19 naturally has a tendency to bind on the guide 20 that resists the lateral movement referred to, so that this binding action may, likewise, be reduced by inclining the guides toward the roadway.

What I claim is:

1. In a railway crossing guard, an arm pivoted to swing vertically and horizontally and adapted to be positioned across a roadway, means for yieldingly resisting horizontal movement of said arm, a cable fixedly attached at its ends to said arm and adapted to be engaged by a vehicle approaching the crossing and preventing impact of said vehicle against the arm, and means for yieldingly supporting the intermediate portion of said cable in spaced relation to said support.
2. In a railway crossing guard, an arm pivoted to swing vertically and horizontally and adapted to be positioned across a roadway, means for yieldingly resisting horizontal movement of said arm, a cable fixedly attached at its ends to said arm, and means

for yieldingly supporting the intermediate portion of said cable in spaced relation to said arm at a plurality of points intermediate the ends of the arm, the intermediate portion of said cable being adapted to be engaged by a vehicle approaching the crossing to prevent impact of said vehicle against said arm.

3. In a railway crossing guard, a horizontally swingable arm adapted to be positioned across a roadway, means for yieldingly resisting swinging movement of said arm, a cable fixedly attached at its ends to said arm with its intermediate portion deflected in a horizontal plane toward said arm, and a series of attaching devices secured to the intermediate portion of the cable and in said arm, said devices being slideable in a horizontal plane in the arm to permit additional flexing of the cable upon impact of a vehicle.
